UNITED STATES PATENT OFFICE.

ISHAM RANDOLPH, OF CHICAGO, ILLINOIS.

RAILROAD-SWITCH AND SIGNAL-OPERATING APPLIANCE.

SPECIFICATION forming part of Letters Patent No. 431,726, dated July 8, 1890.

Application filed February 17, 1890. Serial No. 340,792. (No model.)

To all whom it may concern:

Be it known that I, ISHAM RANDOLPH, a citizen of the United States, residing at Chicago, in the county of Cook and State of Illinois, 5 have invented a new and useful Improvement in Appliances for Operating Railroad Switches, Signals, and the Like, of which the following is a specification.

My invention relates to an improved appliance which may be used with advantage in various connections for different purposes, but which I have devised especially for use on railroads as a means for operating switches, signals, detector-rails, and the like. While 10 the foregoing title, therefore, is selected for the sake of brevity and as indicating the purpose for which my improvement is especially designed, it is not to be understood as indicating the only uses of which my improvement 15 is susceptible; nor do I wish to be understood as intending to limit it to such particular connection for its application.

The construction in which my improved appliance consists involves, in its broadest 20 sense, a cam-bar adapted to be reciprocated lengthwise and confined laterally, and which bar, by moving it longitudinally in either direction through a predetermined distance, imparts motion to a crank or lever, which the 25 bar at a given point disengages from the cam and locks, and the further movement of which bar in the same direction causes its cam to re-engage the crank or lever and move the latter until the play in that direction of the 30 bar is completed. The movement of the cam-bar in the opposite direction from that described produces the same motions of the cam or lever, but in the opposite direction.

For the sake of enabling my improvement 35 to be clearly understood and of convenience in presenting it, I illustrate it in the accompanying drawings in its application to a railroad-switch and detector-bar and in connection with my improved railroad-switch appliance 40 for which Letters Patent of the United States No. 410,332 were granted me on the 3d day of September, 1889.

In the drawings, Figure 1 is a view in the 45 nature of a diagram, showing my improvement as operatively applied to a railroad detector-bar and switch; Fig. 2, a section taken

on the line 2 of Fig. 1, viewed in the direction of the arrow and enlarged; Fig. 3, a broken view in the direction of the arrow at 3 on Fig. 1 of the outer side of the rail and detector-bar mechanism applied to it, being an enlarged representation over that in the first figure; Fig. 4, a plan view of my improved appliance, showing the cam-bar and lever in one of their extreme relative positions; Fig. 5, a 55 similar view of the same, showing the cam-bar and lever in their intermediate relative positions, wherein the lever is locked, and thereby, also, the detector-bar in its raised position; and Fig. 6, a plan sectional view of 60 my improved appliance, showing the cam-bar and lever in the other of their extreme relative positions.

My improved appliance A involves as the details of its construction a bed-plate A', 70 having guides, preferably in the form of ordinary flanged guide-rollers r r', in pairs at opposite sides of its center, preferably near the opposite ends of the bed-plate, as shown, a crank arm or lever B, imposed upon the 75 bed-plate to extend crosswise thereof and fulcrumed thereto, as at x, being provided at or near the end adjacent to the side of the bed-plate, having the guide r', with stops q and q', preferably in the form of flanged rollers, 80 like the guide-rollers already described, and a bar C, having a tongue p, extending from the edge nearest the end of the lever B, provided with the stops, and notches o and o' in its edge at opposite sides of the tongue, the 85 notches being sufficiently wide to admit the stops q and q' and of a depth about corresponding with the extent of the predetermined movement of the lever B from its right-angular position with reference to the 90 base A', the notches being preferably rounded at their bases to conform to the shape of the roller form of the said stops employed. The lever B may have a lateral branch n, with the end m or without the latter, or the branch n 95 may be omitted and only the end m provided, the provision of both serving a minor purpose, hereinafter described. The bar C is confined at its edges between the guides r at the one side and the guides r' at the other. 100

The device thus described may be placed in operative position at the side of a railroad-

track E, preferably near the switch E', and at the outer side of the track.

D is the detector mechanism, which may involve any ordinary or suitable construction, 5 that shown comprising the well-known combination formed of a series of brackets l, secured at intervals, in the manner represented in Figs. 2 and 3, to the outer side of a rail v, each having pivoted to it near its base one 10 end of a toggle-lever t, the other end being pivoted to the side of the detector-bar k, and all the toggles being connected and operative together at their joints by a bar t', which may be termed the "draw-bar," whereby movement 15 of the latter lengthwise a certain distance in either direction straightens all the toggles and lifts the detector-bar to extend above the rail v, and movement thereof beyond such distance or in the opposite direction 20 bends the toggles, and thereby lowers the detector-bar to its normal position. A bar i, pivotally secured at its center in horizontal position, as indicated in Fig. 1, forms a connecting medium between the draw-bar 25 t' of the detector mechanism and the lever B, being connected from one end with the former through a rod i' at an eye t' on the draw-bar and with the latter through a rod i'. The connection of the rod i' with the lever B may 30 be either at the end m or branch n, as will best serve convenience in the particular relative location of parts of the mechanism.

Though my improved device may be applied to the switch E' by various means to 35 render it operative in its purpose, I prefer to apply it through the medium of the appliance F, for which Letters Patent have already been granted me, as aforesaid, and which, briefly described, involves the following construction: A bed-plate w, supporting a horizontally-reciprocating bar w', confined between guides u and u', the first-named carrying anti-friction rollers bearing against the adjacent edge of the reciprocating bar, recessed as 40 shown, and a toggle-lever G, having the arms s and s' pivotally connected at one end with the bar w' and joined at their other or free ends, provided with elongated slots, by a bar s', pivoted at its center to the bed-plate and 45 engaging at its opposite ends through studs with the elongated slots in the ends of the toggle-bars. A connecting-bar H connects the toggle-lever device with the switch E'.

With my improvement applied in the manner thus described the bar w' of the device 50 F may form a link connected by a suitable medium h' (rod, wire, cable, or the like) with a similar medium h, passed around a stationary pulley g beyond the appliance A, and 55 connected at its ends with the lever system (not shown, but forming a well-known arrangement for operating switches) at the operating-station.

The operation is then as follows: By pulling 60 upon the connecting medium h in the direction indicated by the arrow in Fig. 1 the bar C (with the other parts of my improved

device and of the mechanisms connected therewith in the relative positions illustrated) is accordingly moved lengthwise, provided there 70 be no car or train of cars on the rail v of the track E, though if there be a car or train of cars on the track the detector-bar k will be stopped against rising under the strain on the medium h, thereby also obstructing operation of the appliances F and A, the detector then exercising the function of a lock against throwing of the switch E'. If the conditions, however, permit the bar C to be moved as described, the notch o' therein engaging with 75 the stop q' on the crank or lever B, turns the latter on its pivot x until the said stop, owing to the arc described by the lever B is moved out of the notch o', which, according to the relative arrangement of parts, takes place 80 when the lever reaches a position at or about at a right angle to the base A'. This movement of the lever B turns the pivoted bar i through the medium of the rod i', and through the rod i' pulls upon the draw-bar t' of the 85 detector device D, straightening the toggles t, and thereby effecting the rise of the detector-bar k. The described movement of the bar C draws with it the bar w' of the device F, and through the toggle device G thereof 90 and connecting-bar H throws the switch E'. As soon as the stop q' has left the notch o', the bar C, by continuing the pull upon it, continues to move in the same direction to complete the throw of the switch without 95 continuing the movement of the lever B, which is locked in its right-angular position referred to by the straight portions of the outer edge of the bar C at opposite sides of the notches o' and o moving against the stops q' and q, 100 which are then in line with the guides r', as shown in Fig. 5, and, since they in that position, prevent the lever B from being turned by the strain upon it of the weight of the detector-bar k exerted through the mechanism 105 connecting it with the lever B, the locking of the latter by its stops q and q' being against the straight portions of the edge of the bar C, also locks the toggles t against bending or 110 collapsing at their joints under the weight of the detector-bar, which is thus held in its raised position until the switch is almost half-way thrown. On the tongue p coming in contact with the stop q, since the tongue projects 115 the required distance beyond the adjacent 120 edge of the bar C, continuation of the longitudinal movement of the latter turns the lever B until the stop q enters fully into the notch o, this turning of the lever effecting, through the bar i and its connections i' and i', sufficient 125 strain on the draw-bar t' to cause it to bend the toggles t toward their opposite collapsed condition, (represented by dotted lines in Fig. 3,) the weight of the detector-bar, after such bending of the toggles has once been started, 130 assisting the continuation of their collapse to lower the detector-bar to its normal position, and thus reducing the strain required to be exerted on the initial switch-operating le-

versystem (hereinbefore referred to as not being shown) for effecting the complete throw of the switch.

To produce the throw of the switch E' in the opposite direction from that described, the necessary strain on the connecting medium *h* has obviously to be exerted in the direction contrary to that indicated by the arrow in Fig. 1, when the parts perform their functions in the manner explained, but in the contrary direction.

As will be seen, the bar C, owing to its construction and the manner of its operation, is in the nature of a cam-bar.

15 What I claim as new, and desire to secure by Letters Patent, is—

1. In an appliance A, the combination of a cam-bar C, confined laterally and movable longitudinally between guides *r* and *r'*, and a lever B, fulcrumed in place to extend across the cam-bar and provided at its end beyond the cam side of the bar C with stops *q* and *q'*, engaging with the said side of the cam-bar at opposite sides of the cam thereon and forming with the cam-bar a lock for the lever against its movement in either direction, substantially as and for the purposes set forth.

2. In an appliance A, the combination of a base A', a cam-bar C, confined laterally and movable longitudinally between guides *r* and *r'*, a lever B, fulcrumed toward one end to the base at one side of the cam-bar and extending at its opposite end beyond the cam-bar and there provided with stops *q* and *q'*, bearing against the cam side of the bar C at opposite sides of the cam thereon and forming with the cam-bar a lock for the lever against its movement in either direction, substantially as and for the purposes set forth.

3. In an appliance A, the combination of a base A', a cam-bar C, confined laterally and movable longitudinally between guides *r* and *r'*, and a lever B, provided with a branch *n* near its end *m* and fulcrumed near the said end to the base at one side of the cam-bar extending across the latter and provided at its opposite end with stops *q* and *q'*, engaging with the cam side of the bar C at oppo-

site sides of the cam thereon and forming with the cam-bar a lock for the lever against its movement in either direction, substantially as and for the purposes set forth.

4. In an appliance A, the combination of a bar C, provided in one side with the notches *o* and *o'* and the intermediate tongue *p*, and confined laterally and movable longitudinally between guides *r* and *r'*, and a lever B, fulcrumed in place to extend across the bar C and provided at its end adjacent to the notched side of the said bar with stops *q* and *q'*, engaging with the said notched side of the bar C, substantially as and for the purposes set forth.

5. An appliance A, comprising, in combination, a base A', a bar C, confined laterally and movable longitudinally between guides *r* and *r'* on the base and provided in one side with notches *o* and *o'* and the intermediate tongue *p*, and a lever B, fulcrumed at one side of the bar C to the base, extending across the said bar and provided at its end adjacent to the notched side of the bar with stop-rollers *q* and *q'*, substantially as and for the purposes set forth.

6. In combination with a railroad-track having a switch E' and a detector device D, an appliance A, comprising a base A', a bar C, confined laterally and movable longitudinally between guides *r* and *r'* on the base, and provided in one side with notches *o* and *o'* and the intermediate tongue *p*, the said bar being connected from opposite ends, respectively, with the switch and operating mechanism, and a lever B, fulcrumed at one side of the bar C to the base A' and connected with the detector device and extending across the said bar and provided at its end adjacent to the notched side of the bar with stop-rollers *q* and *q'*, the whole being constructed and arranged to operate substantially as described.

ISHAM RANDOLPH.

In presence of—

J. W. DYCENFORTH,
M. J. FROST.
